CONTROL SYSTEM

Clyde E. Stewart, Upper Darby, Pa., assignor to
 General Electric Company, a corporation of
 New York

Application February 12, 1937, Serial No. 125,404

6 Claims. (Cl. 175—320)

My invention relates to control systems and particularly to a system for controlling a rapidly operating device such as a rotary selector switch so that it may be positively stopped in any 5 of a plurality of its positions, and one object of my invention is to provide an improved control system for accomplishing this result.

My invention will be better understood from the following description when taken in connection 10 with the accompanying drawing, the single figure of which diagrammatically illustrates a rotary selector switch control system embodying my invention, and its scope will be pointed out in the appended claims.

Referring to the accompanying drawing, 1 represents a rotary selector switch of any suitable type, examples of which are well known in the art. As shown in the drawing, the switch 15 includes a bank of stationary contacts 2 and a co-operating movable wiper 3 which is arranged to be moved into engagement with successive contacts by a ratchet 4 that is operated in any suitable manner each time an associated operating magnet 5 is de-energized.

In accordance with my invention, I provide an 20 improved operating control circuit for the magnet 5, whereby when a starting circuit is completed for the winding 9 of the magnet 5, the winding 9 is intermittently energized to move 25 the wiper 3 to a desired contact and when the wiper engages this desired contact, the circuit of the magnet 5 is controlled in such a manner as to insure that the wiper 3 remains on the desired 30 stationary contact. For accomplishing this result, I provide a control relay 6 which has two 35 differential windings 7 and 8. The winding 7 is connected in parallel with the winding 9 of the operating magnet 5 and the winding 8 is connected in series with the parallel connected windings 7 and 9 by the normally closed contacts 10 of the operating magnet 5. Also a resistor 11 is 40 connected in parallel with the winding 8 of the relay 6 by the normally closed contacts 12 of the relay 6. A suitable start switch 13 is provided 45 which when closed supplies the operating potential to the circuit of the magnet winding 9.

Since the operating magnet 5 requires a relatively large current to operate it, the resistance of the energizing circuit of this magnet has to 50 be relatively low. This result is obtained by making the resistance of the resistor 11 relatively low. The resistance of the windings 7 and 8 are made relatively high so that during the stepping 55 operation of the operating magnet 5 only a small current flows through these two differential windings and these two windings are also designed so that the resultant ampere turns produced by these small currents flowing through them during the stepping operation of the operating magnet 5 are substantially zero in order

to insure that the relay 6 remains in its normally de-energized position.

Associated with each stationary contact 2 is a circuit closing device 14 which, when closed, connects the associated contact 2 to the source of control current so that when the wiper engages the contact 2 a low resistance shunt circuit is completed around the parallel connected windings 7 and 8. This shunt circuit reduces the voltage drop across the winding 9 of the magnet 5 so that it cannot pick up and consequently further movement of the wiper 3 is prevented as long as the circuit closing device 14 associated with the contact 2 with which the wiper 3 is in engagement remains closed. The closing of the shunt circuit around the winding 7 of the relay 6 also increases the voltage impressed across the winding 8 so that the resultant ampere turns produced by the two differential windings 7 and 8 are increased to a sufficient value to cause the 20 relay 6 to open its contacts 12 and thereby disconnect the resistor 11 from across the control source. Since the resistance of the winding 8 is materially greater than the resistance of the resistor 11, the control source has to supply only 25 a small current to maintain the switch in any of its off-normal positions.

The operation of the arrangement shown in the drawing is as follows: It will be assumed that the switch 1 is in its normal position as shown, 30 and that it is desired to cause the wiper 3 to engage one of its off-normal contacts 2. The circuit closing device 14 associated with this desired off-normal contact 2 is closed so as to connect the positive terminal of the control source 35 directly to this contact 2. Then the start switch 13 is closed to complete a circuit from the positive terminal of the control source through the switch 13, the windings 9 and 7 in parallel, the contacts 10 of magnet 5, and then to the negative 40 terminal of the control source through the winding 8 of relay 6, and also through the contacts 12, and resistor 11 in series. The current in this circuit is sufficient to cause the magnet 5 to operate and open its contacts 10. The currents 45 through the windings 7 and 8, however, are such that the ampere turns of the two windings are substantially equal and opposite and therefore the relay 6 does not operate to open its contacts 12. The opening of the contacts 10 effects the 50 de-energization of the magnet 5, which in returning to its de-energized position, operates the ratchet 4 to move the wiper 3 from its normal position to its first off-normal position. As soon as the magnet 5 has reached its normal position 55 and has closed its contacts 10, the heretofore described circuit through the windings 9, 7, 8 and resistor 11 is again completed. In this manner, the magnet 5 is intermittently energized and de-energized until the wiper 3 engages the contact 60

2 which is connected directly to the positive terminal of the control source by its associated circuit closing device 14. When the wiper 3 engages this contact 2, a low-resistance shunt circuit is completed around the windings 7 and 9 so that substantially the full potential of the control source is impressed across winding 8 of the relay 6. Consequently, the magnet 5 is prevented from operating but the relay 6 operates to 10 open its contacts 12 and disconnect the resistor 11 from across the control source.

The relay 6 may also be provided with other contacts 16 which may be connected in any suitable manner so as to effect the operation of another control device (not shown) which it is desired to operate when the switch 1 has stopped in an off-normal position.

While I have, in accordance with the patent statutes, shown and described my invention as applied to a particular system and as embodying various devices diagrammatically indicated, changes and modifications will be obvious to those skilled in the art, and I therefore aim in the appended claims to cover all such changes and modifications as fall within the true spirit and scope of my invention.

What I claim as new and desire to secure by Letters Patent of the United States is:

1. In combination, a rotary switch having a movable wiper and a plurality of stationary contacts, means including a magnet for moving said wiper into successive engagement with said contacts, a winding for said magnet, a control relay having two differential windings, means for completing an energizing circuit for said magnet winding with one of said relay windings connected in parallel with said magnet winding and the other of said relay windings connected in series with said magnet winding, means responsive to the energization of said magnet for opening said energizing circuit, and means for closing a shunt circuit around said parallel connected magnet and relay windings when said wiper engages a predetermined contact.

45 2. In combination, a rotary switch having a movable wiper and a plurality of stationary contacts, means including a magnet for moving said wiper into successive engagement with said contacts, a winding for said magnet, a control relay having two differential windings, means for completing an energizing circuit for said magnet with one of said relay windings connected in parallel with said magnet winding and the other of said relay windings connected in series with said magnet winding, contacts in said energizing circuit, means responsive to the energization of said magnet for opening said last mentioned contacts, a parallel circuit around said other of said relay windings including an impedance, contacts in said parallel circuit controlled by said relay, and means for closing a shunt circuit around said parallel connected magnet and relay windings when said wiper engages a predetermined contact.

50 3. In combination, a rotary switch having a movable wiper and a plurality of stationary contacts, a magnet, a winding for said magnet, means including said magnet for moving said wiper into successive engagement with said contacts, a control relay having two differential windings of relatively high impedances, means for completing an energizing circuit for said magnet winding with

one of said relay windings connected in parallel with said magnet winding and the other of said relay windings connected in series with said magnet winding, contacts in said energizing circuit, means responsive to the energization of said magnet for opening said last mentioned contacts, and means for closing a shunt circuit around said parallel connected magnet and relay windings when said wiper engages a predetermined contact.

5 4. In combination, a rotary switch having a movable wiper and a plurality of stationary contacts, a magnet, means including said magnet for moving said wiper into successive engagement with said contacts, a winding for said magnet, a control relay having two differential windings of relatively high impedances, means for completing an energizing circuit for said magnet winding with one of said relay windings connected in parallel with said magnet winding and the other of said relay windings connected in series with said magnet winding, contacts in said energizing circuit, means responsive to the energization of said magnet for opening said last mentioned contacts, a parallel circuit around said other of said relay windings including a relatively low impedance device, contacts in said parallel circuit controlled by said relay, and means for closing a shunt circuit around said parallel connected magnet and relay windings when said wiper engages a predetermined contact.

20 5. In combination, a rotary switch having a movable wiper and a plurality of stationary contacts, means including a magnet having a relatively low resistance winding for moving said wiper into successive engagement with said contacts, a control relay having two differential windings of relatively high substantially equal resistances, a resistor having a relatively low resistance value, means for completing an energizing circuit for said magnet winding with one of said relay windings connected in parallel with said magnet winding and the other of said relay windings connected in series with said magnet winding and said resistor connected in parallel with said other of said relay windings, contacts in said energizing circuit connected in series with said relay windings, means responsive to the energization of said magnet for opening said last mentioned contacts, means for closing a shunt circuit around said parallel connected magnet and relay windings when said wiper engages a predetermined contact, contacts in series with said resistor in the parallel circuit around said other of said relay windings, and means for opening said last mentioned contacts when a predetermined unbalance occurs in the energizations of said relay windings.

25 6. In combination, a rotary switch having a movable wiper and a plurality of stationary contacts, means including a magnet for moving said wiper into successive engagement with said contacts, a winding for said magnet, means for completing a circuit including said magnet winding, means responsive to the energization of said magnet for opening said circuit, means for completing a shunt around said magnet winding when said wiper engages a predetermined contact, and means controlled by said magnet for increasing the resistance in said circuit after said shunt is completed.

CLYDE E. STEWART.
